C. S. OLSON

WRENCH

Filed Oct. 27, 1923

Fig. 2.

CHAS. S. OLSON.

Geo. J. Edwards

Attorney

UNITED STATES PATENT OFFICE.

CHARLES S. OLSON, OF DULUTH, MINNESOTA.

WRENCH.

Application filed October 27, 1923. Serial No. 671,263.

To all whom it may concern:

Be it known that I, CHARLES S. OLSON, a citizen of the United States, residing at Duluth, in the county of St. Louis and State 5 of Minnesota, have invented certain new and useful Improvements in Wrenches, of which the following is a specification, reference being had therein to the accompanying drawing.

- 10 This invention relates to wrenches and has special reference to a wire splicing wrench, such as used in connection with the splicing of high power electric transmission lines.
- 15 The principal object of the invention is to produce an efficient wrench of this character which is as easy of adjustment and manipulation as possible.

20 Other objects and advantages of the invention will appear in the further description thereof.

25 Referring now to the accompanying drawing, forming part of this application, and in which like reference characters indicate like parts:

30 Figure 1 is a side elevation of the head of one of the improved wrenches, showing the jaws thereof open for the reception of electric cables to be spliced; and

35 Figure 2 is a sectional view taken on the line 2—2, Figure 1, looking upwardly.

1 represents the head of the wrench, with in the spaced jaws 2 and 3 of which is rotatably mounted the laterally projecting ratchet hub 4 of the jaw 5 of the auxiliary head, the latter comprising the two jaws 5 and 6 which are pivotally united upon the pin 7. The ratchet hub 4 is formed integral with the jaw 5, and has an open throat or mouth indicated at 8 which is elongated and the upper face of which is of double scalloped form, as clearly seen in Figure 1. This shape extends entirely through the ratchet hub and the jaw 5, while the lower face of the ratchet hub is comparatively straight, though arched upwardly as at 9, and gracefully joins the rearmost scallop of the upper surface. The hub 4 is held in position within the head 1 by its annular stepped shoulder 10 fitting within a registering recess in the head, and the outermost face of said hub is provided with a flange 11, fitting within a like recess 12 upon the opposite side of the head 1 and firmly united with the face of the hub by suitable screws 13, it being obvious that when the plate 11

is removed the auxiliary head may be withdrawn laterally from the head 1.

The jaws 5 and 6 of the auxiliary head are adjustably united by means of the bolt 60 14 which is screw threadedly mounted within the jaw 5 and protrudes entirely through the jaw 6, said protruding extremity also being externally screw threaded for the reception of the adjusting crank 15, and where 65 this bolt passes through the jaws 5 and 6 it is surrounded with an annular recess, indicated at 16, upon either jaw, the same being for the reception of the expansive spiral spring 17 which normally tends to hold the 70 jaws separated or open. To provide for the parallel opening and closing of these jaws, the one 6 is provided with an elongated hole 18, through which the pin 7 extends, providing not only pivotal adjustment of the 75 jaws, but the parallel movement of same; thus when the crank or handle nut 15 is unscrewed, the jaws 5 and 6 will open, and if the auxiliary head is in axial alignment with the head 1 the open jaws thereof will be 80 positioned to receive the cables for splicing, as shown in Figure 1, and the cable contacting end of the jaw 6 is shaped identical with that of the jaw 5.

A reciprocal pawl 19 is mounted within 85 the head 1 and held normally in engagement with the circumferential face of the ratchet hub 4 by the expansive spiral spring 20, said pawl being manipulated by the shank knob 21 protruding through an elongated 90 slot 22 in the side of the head 1.

This pawl permits, as is evident, of the anti-clockwise rotation of the head 1, while the clockwise rotation of said head will carry with it the auxiliary head, and, if the 95 wrench is clamped upon the sleeved cables for forming a splice, it will forcibly twist said sleeve, as shown in Figure 2, these cables being indicated at 23, and the copper sleeve at 24, this latter being common and 100 well known in the art.

The head 1 is provided with an externally screw threaded shank 25 for the reception of any form of handle for example an internally screw threaded piece of tubing or pipe 105 illustrated at 26, which may be of any desired length or size to act as a convenient handle, and it is well known that the copper sleeve into which the ends of the cables are placed is of oval or elliptical form in cross 110 section.

Having thus described my invention, what

I claim and desire to secure by Letters Patent, is:

A wrench of the character described having a head, an open sided hub-like saw tooth ratchet mounted within the head the hub portion of said ratchet being stepped to rotatably register with a like stepped portion in the head of the wrench, a removable holding plate on the extreme end of that portion of the hub extending into the head of the wrench, a gripping jaw formed integral with the end of the hub externally of one side of the head of the wrench, and a second

jaw adjustably carried in parallel relation to and by the first mentioned jaw, and a spring controlled pawl mounted longitudinally of and within the head, and operable from that side of the head opposite the gripping jaws for releasing the ratchet.

In testimony whereof I hereunto affix my signature in the presence of two witnesses.

CHARLES S. OLSON.

Witnesses:

S. C. BRONSON,
S. GEO. STEVENS.
